E. R. BURTNELL

INTERNAL COMBUSTION ENGINE

Filed Jan. 8, 1925

Inventor: —
Everett R. Burtnett
By Martin Smith atty.

UNITED STATES PATENT OFFICE.

EVERETT R. BURTNETT, OF LOS ANGELES, CALIFORNIA, ASSIGNOR, BY DIRECT AND MESNE ASSIGNMENTS, TO THE AUTOMOTIVE VALVES CO., OF LOS ANGELES, CALIFORNIA, A VOLUNTARY TRUST.

INTERNAL-COMBUSTION ENGINE.

Application filed January 8, 1925. Serial No. 1,176.

My invention relates generally to internal combustion engines and more particularly to a common compression and combustion clearance chamber that is formed in the cylinder head portion of the engine and which clearance chamber connects the head or inner end portions of the adjacent members of a pair of piston chambers, the principal objects of my invention are, to form the 5 common clearance chamber in the head portion of the engine structure so that it is wholly surrounded by a cell or chamber through which a cooling fluid, such as water, may be circulated for the rapid convection of the heat that is developed within 10 said chamber; to provide a construction of the character referred to, wherein the common clearance chamber is connected to the head ends of the adjacent piston chambers by short throats, that are spaced apart so as to provide a cooling fluid circulation 15 space between and entirely around them; further, to arrange the spark plug receiving lug between the wall of one of the throats and the outer wall of the head structure so that said lug is entirely surrounded by a cooling fluid circulation chamber and, further, to form the underside of the bottom portion of the wall of the common clearance 20 chamber so as to preclude the possibility of formation and lodgment of steam or air bubbles on the underside of said common clearance chamber.

With the foregoing and other objects in 25 view, my invention consists in certain novel features of construction and arrangement of parts that will be hereinafter more fully described and claimed and illustrated in the accompanying drawings in which:

Fig. 1 is a horizontal section taken 30 through the center of the common compression and combustion clearance chamber.

Fig. 2 is a vertical section taken on a longitudinal plane through the center of the 35 head of a cylinder block and which head is provided with the common compression and combustion clearance chamber contemplated by my invention.

Fig. 3 is a cross section taken on the line 40 3-3 of Fig. 2.

Referring by numerals to the accompanying drawings, 10 designates a cylinder block having formed therein, a pair of combustion

chambers 11 and arranged for operation within said chambers are pistons 12. 55

The walls of block 10 are formed with connected cells or chambers 10^a through which is a fluid cooling medium, such as water is adapted to circulate and these cells or chambers communicate directly with cells or 60 chambers 18 that are formed in the cylinder head 14.

Directly above the pair of chambers 11, head 14 is formed with an upwardly projecting mound-shaped portion 15, the wall 65 of which is provided with a cell or chamber 16 that communicates with cell or chamber 13.

At the top of member 15, this cell or chamber 16 is provided with an outlet 17, 70 to which may be connected a suitable circulation duct (not shown).

Formed in member 15 is a substantially spherical chamber 18 and leading downwardly therefrom are short throats or ducts 75 19 and 20 that communicate directly with the head or inner ends of chambers 11.

These throats are spaced apart, thereby providing a narrow cooling fluid circulation duct or space 21 between them. 80

Inasmuch as chamber 18 is substantially spherical in form, the under surface of the lower portion thereof, curves upwardly in all directions from a central point, consequently there are no flat faces on which air 85 or steam bubbles might collect and form an objectionable heat insulating area.

By arranging the outlet 17 at the top of chamber 16, the flow of cooling fluid is in a general upward direction through chambers 10^a and 16, and this action assists materially in counteracting any tendency of air or steam bubbles to form and collect on the rounded underside of the wall surrounding chamber 18. 95

Formed between the inner and outer walls of members 15 and preferably at a point above throat 20, the latter being in communication with the chamber 11 that is provided with gaseous fuel inlet ports, is a wall 100 22 having a threaded aperture that receives a spark plug 23. This lug is encompassed by cooling fluid circulation chamber 13.

It will be understood that as the pistons 12 travel upward in their respective chambers 11, a charge of gaseous fuel admitted into 105

one of said chambers will be compressed in common clearance chamber 18 and, as the pistons pass high center, the compressed charge will be fired by a spark produced between the terminals of plug 23.

The rise in pressure following combustion of the fuel charge will pass through throats 19 and 20 and impinge the heads of the pistons, thereby driving same downward on 16 their power stroke.

Inasmuch as common clearance chamber 18, throats 19 and lug 20 are encompassed by cooling fluid circulation chambers, the connection of heat from said chamber and 15 throats will be comparatively rapid and, due to the rounded contour of the undersurface of the lower portion of the wall surrounding the common clearance chamber, the formation of heat insulating gas and air bubbles 20 on said undersurface is effectually prevented.

Obviously, the size, form and construction of the common clearance chamber as herein described, may be modified in certain details without departing from the spirit 25 of the invention, the scope of which is set forth in the appended claims.

I claim as my invention:

1. In an internal combustion engine, the combination with a pair of combustion cylinders, the axes of which are parallel, of a head closing the inner ends of the combustion chambers, a common compression and combustion clearance chamber formed in said head inwardly from the surface thereof 35 of that is applied to the head ends of the cylinders which common clearance chamber is spherical in form, short parallel ducts formed in said head and connecting the common clearance space with the combustion 40 chambers, the axes of which ducts are parallel with the axes of the combustion chambers, one of which ducts communicates

directly with the lower portion of the common clearance chamber the other duct being offset with respect to the common clearance 45 chamber so that its upper portion communicates directly with the end of said common clearance chamber and the greatest width of the spherical chamber being substantially greater than the widths of the ducts that 50 connect said chamber with the combustion chambers.

2. In an internal combustion engine, the combination with a pair of combustion cylinders, the axes of which are parallel, of a head closing the inner ends of the combustion chambers, a common compression and combustion clearance chamber formed in said head inwardly from the surface thereof 55 that is applied to the head ends of the cylinders which common clearance chamber is spherical in form, short parallel ducts formed in said head and connecting the common clearance space with the combustion chambers, the axes of which ducts are parallel with the axes of the combustion chambers, one of which ducts communicates directly with the lower portion of the common clearance chamber, the other duct being offset with respect to the common clearance 60 chamber so that its upper portion communicates directly with the end of said common clearance chamber the greatest width of said common clearance chamber being substantially greater than the widths of the ducts 65 that connect said common clearance chamber with the combustion chambers and an ignition means seated in the head and projecting into the upper end of the duct that is offset relative to the common compression 70 and combustion clearance space.

In testimony whereof I affix my signature.

EVERETT R. BURTNELL.
